CLAIM

The ornamental design for a reamer for drilling water wells and the like, as shown and described.

DESCRIPTION

FIG. 1 is a perspective view of a reamer for drilling water wells and the like showing my new design;

FIG. 2 is an end elevational view thereof, the opposite end being identical;

FIG. 3 is a side elevational view thereof;

FIG. 4 is another side elevational view thereof, taken in a place rotated slightly from that of FIG. 3; and

FIG. 5 is another side elevational view thereof, taken in a place rotated slightly from that of FIGS. 3 and 4.
